MULTIPLE RETORT STOKER

Filed Dec. 18, 1943

• 3 Sheets-Sheet 1

The drawing shows a vertical assembly of three identical filter stages. Each stage consists of a rectangular frame labeled '14' containing a stack of pleated filter media labeled '25'. Above the media is a horizontal support plate labeled '27'. A central vertical support structure labeled '28' holds the three stages in alignment. The top stage is shown with an arrow '4' pointing to the right, indicating the direction of flow. The bottom stage is shown with an arrow '4' pointing to the left, indicating the direction of flow for the bottom stage.

MULTIPLE RETORT STOKER

George P. Jackson, Flushing, N. Y., assignor to
Combustion Engineering Company, Inc., New
York, N. Y.

Application December 18, 1943, Serial No. 514,800

6 Claims. (Cl. 110—44)

This invention relates to stokers and particularly to improvements in multiple retort under-feed stokers.

Conventional multiple retort stokers comprise a number of retorts and tuyères extending longitudinally of the furnace and arranged in alternation across the width of the furnace. Each retort is provided at its front end with a ram which reciprocates through a ram box extending from below a fuel hopper into the retort and delivers the fuel dropping into the ram box from the hopper by pushing it into the retort. The fuel is then moved along each retort toward the rear of the furnace by means of pushers which are arranged for reciprocation in the bottom of the retort. The tuyères adjacent each retort deliver air for combustion into the burning mass of fuel being moved along the retort. At the rear ends of the retorts there are overfeed sections that receive the burning fuel from the retorts and tuyères for completing the burning of the fuel before it is delivered to the ash receiving means.

Heretofore the practice in multiple retort stoker construction has been to have an individual ram for each retort. One of the limitations in burning the fuel has been due to the width of the retorts which was established by the width of the ram that feeds it. The width of the ram was made ample to prevent the packing of the fuel in the ram box and because ram boxes are costly to make it was considered desirable to use as few of them as possible which led to increasing their width and that of the retorts to an undesirable degree.

In operation it has been found that the fuel bed forms in ridges longitudinally of the furnace because most of the burning of the fuel occurs above the tuyère surfaces and to a limited extent above the retorts. This is because the air admitted through the tuyères does not completely penetrate the wide fuel bed over the retorts. To partly compensate for this unequal distribution of the air through the fuel bed the stoker must be operated with a thicker fuel bed than would be the case where air admission were more uniform. Furthermore, as the fuel is carried along through the furnace by the action of the pushers, the action of the pushers has been found to be effective in distributing and moving the fuel above the retorts but not so effective in moving the fuel along the top of the adjacent tuyère rows. Due to the present widths of the tuyères the longitudinal movement along the middle of the tuyères is found to be sluggish and if the fuel ash becomes soft at a comparatively low temperature and has clinking tendencies, the fuel does not move down the middle of the stoker tuyères but adheres thereto partially shutting off the air and further aggravating the difficulties in operating the stoker.

An object of this invention is to provide an improved multiple retort stoker to overcome the above difficulties.

In the accompanying drawings:

5 Figure 1 is a sectional elevation taken longitudinally through a stoker embodying the invention;

10 Figure 2 is a sectional plan view on line 2—2 of Figure 1;

15 Figure 3 is a section on line 3—3 of Figure 1;

Figure 4 is a section on line 4—4 of Figure 2; and

Figure 5 is a view similar to Figure 2 showing another embodiment of the invention.

15 The operating parts of the stoker shown in Fig. 1 are in general the same as those disclosed in the patent to Zinkernagel et al., 2,164,100, issued June 27, 1939. The stoker drive includes a drive shaft 10 operating through reduction gearing, 20 designated as a whole by the numeral 11 in Figure 1, to drive a crank shaft 12 having cranks 13 for reciprocating the rams 14 in ram boxes 15 through connecting rods 16. Other connecting rods 17 act through bell-cranks 18 and the adjustable stepped cams 20 to actuate the push rod assembly 21 to reciprocate the fuel pushers 22 in the retorts 25.

25 As appears in Fig. 2, the retorts 25 and tuyères 26 extend longitudinally of the stoker and are arranged in alternation. Retorts 25 are grouped preferably two to a ram box 15; thus one ram 14 as it reciprocates delivers fuel from the hopper through one ram box 15 to the forward ends of two adjacent retorts 25. The pushers 22 at the

30 bottom of the retorts advance the fuel to the rear of the stoker. Alternating with the retorts 25 are the tuyères so that there is a tuyère 26 between the two retorts 25 fed by one ram 14 and also a tuyère 26A between each such pair of retorts and the adjacent pair of retorts, the tuyères 26A thus being opposite the spacers 28 intervening between two rams 14 and associated boxes. The forward ends 27 of the tuyères 26 facing the

35 rams 14 are spaced rearwardly from the rams and shaped wedge-like to divide the fuel flowing from the ram box 15 into two separate streams, one for each of two adjacent retorts 25. Ram boxes 15 are spaced apart transversely of the stoker and 40 one tuyère 26A is in longitudinal alignment with the space intermediate the ram boxes. Since this intervening space 28 may be wider than the aligned tuyère 26A the latter may be flared at its front end so as to meet flushly with the sides of 45 the adjacent ram boxes 15 and form a smooth side wall for the flow of the fuel therealone.

45 Figs. 3 and 4 show the tuyères 26 superimposed on wind boxes 29 which support them. Fig. 3 shows a cross-section through the front 50 tapered end 27 of a tuyère 26 which divides the

flow of fuel from the ram box 15 to the two adjacent retorts.

In Figure 5 showing a modification of the invention several rams 34 are arranged side by side transversely of the stoker in a single ram box 35, there being no partitions between rams 34. Consequently the fuel is delivered substantially uniformly across the width of the stoker. The rams 34 deliver the coal from the hopper to the retorts 25 but do not all move forwardly at the same time. The ram movements preferably alternate and are so timed that a substantially continuous load will be transmitted to the driving mechanism of all the rams. The front ends 27 of all of the tuyères 26 facing the rams 34 are shaped wedgelike to divide the fuel delivered by the rams 34 into the adjacent retorts 25.

In operation, the improved stoker overcomes the difficulties outlined at the beginning of this specification because both the tuyères and retorts have been reduced in width compared to conventional arrangements while the advantages of the wide rams and ram boxes as to cost and non-packing of fuel have been retained. Preferably the tuyères and retorts are made of about the same width and due to their being much narrower than heretofore, the distribution across the stoker of air through the fuel bed is more uniform. The narrower width of the fuel bed above the retort bottom permits a better penetration of the air therethrough. The narrower width of the fuel bed above a tuyère assures a more uniform movement along the stoker of the fuel covering the entire width of the tuyère even when a clinkering coal is used because it is drawn along by the sides of the body of moving coal in the retorts. Consequently the air stoppage over a tuyère by the fuel clinkering to the middle of its top surface is avoided. The improved stoker therefore provides a more uniform burning of the fuel throughout the entire fuel bed.

What I claim is:

1. In an underfeed stoker having a plurality of spaced pairs of retorts with tuyères intervening between the retorts of each pair spaced transversely of the stoker of relatively narrow width and of substantial length; a fuel hopper and ram boxes spaced transversely of the stoker extending from said fuel hopper to the front ends of both retorts of each pair; a reciprocating ram in each box for delivering fuel from the hopper through the ram box to said retorts; means at the end of each tuyère facing said rams shaped to divide the fuel flow delivered thereby into the adjacent retorts; means for reciprocating the rams; reciprocating pushers in the retorts for moving the fuel toward the rear thereof; means for reciprocating said pushers; other tuyères disposed in the spaces between adjacent pairs of retorts and aligned with the spaces between ram boxes; and means for delivering air through all of the tuyères into the fuel above the adjacent retorts and tuyères.

2. In an underfeed stoker having retorts and tuyères arranged in alternation transversely thereof; a fuel hopper; a ram box extending the full width of the stoker communicating with the front ends of all the retorts; a plurality of reciprocating rams for delivering fuel from the hopper through said ram box to said retorts; means at the front ends of the tuyères facing the rams spaced therefrom and shaped to divide the fuel flow delivered thereby into adjacent retorts; means for reciprocating the rams; means in the

retorts for moving the fuel toward the rear thereof; and means for delivering air through the tuyères into the fuel above the adjacent retorts and tuyères.

3. In an underfeed stoker having retorts and tuyères arranged in alternation transversely thereof; a fuel hopper; a ram box extending the full width of the stoker communicating with the ends of all the retorts; a plurality of adjacent contacting reciprocating rams in said ram box each delivering fuel from the hopper through said ram box to at least two retorts; means at the tuyère ends facing the rams spaced therefrom and shaped to divide the fuel therefrom into the adjacent retorts; means for reciprocating the rams; means in the retorts for moving the fuel toward the rear thereof; and means for delivering air through the tuyères into the fuel above the adjacent retorts and tuyères.

4. In an underfeed stoker having a multiplicity of retorts and tuyères of relatively narrow width and of substantial length arranged in alternation transversely of the stoker; a fuel hopper and a conduit extending therefrom to the front ends of at least two adjacent retorts; feeding means for delivering fuel from the hopper through the conduit to said retort ends; means in each of the retorts for advancing fuel longitudinally along the retorts and the adjacent tuyères; means positioned between said two retorts and facing said feeding means in spaced relation to the latter and shaped to divide the fuel flow from said feeding means into the adjacent retorts; means for operating said feeding means, means for operating said fuel advancing means; and means for delivering air through the tuyères into the fuel above the adjacent retorts and tuyères.

5. In an underfeed stoker having a multiplicity of retorts and tuyères of relatively narrow width and of substantial length arranged in alternation transversely of the stoker; a fuel hopper and a ram box extending therefrom to the front ends of at least two adjacent retorts; a reciprocating ram for delivering fuel from the hopper through the ram box to said retort ends; reciprocating pushers in each of the retorts for advancing fuel longitudinally along the retorts and the adjacent tuyères; means positioned between said two retorts and facing said ram in spaced relation to the latter and shaped to divide the fuel flow from said ram into the adjacent retorts; means for reciprocating said ram; means for reciprocating said pushers; and means for delivering air through the tuyères into the fuel above the adjacent retorts and tuyères.

6. In an underfeed stoker having a multiplicity of retorts and tuyères of relatively narrow width and of substantial length arranged in alternate parallel rows transversely of the stoker; a fuel hopper and a ram box extending therefrom to the front ends of each of two adjacent retorts; a reciprocating ram for delivering fuel from the hopper through each ram box to said retort ends; reciprocating pushers in each of the retorts for advancing fuel longitudinally along the retorts and the adjacent tuyères toward the rear thereof; means positioned between each said two retorts and facing said rams in spaced relation to the latter and shaped to divide the fuel flow from said rams into each of the adjacent two retorts; means for reciprocating said rams; means for reciprocating said pushers; and means for delivering air through the tuyères into the fuel above the adjacent retorts and tuyères.

GEORGE P. JACKSON.
